UNITED STATES PATENT OFFICE.

ROY E. NICHOLSON, OF DETROIT, MICHIGAN.

ANCHORING DEVICE FOR HAND RAILS AND THE LIKE.

Application filed April 3, 1924. Serial No. 703,862.

This invention relates to anchoring devices for hand rails and the like adapted to be inserted in concrete or other similar base, and the object is to provide a simple and inexpensive device of the character stated which consists of a hollow base member adapted to be anchored in the concrete and having an adjustable member threaded for the reception of the rail end and adjustable with the axis of the threaded apertures at various angular positions thereby truing the same relative to the axis of the hand rail or structure to be inserted therein.

A further object is to provide a device that may be secured to the mold boards utilized in forming a concrete or similar plastic structure to support the same in proper position while the plastic material is being placed.

In structures of this character formed by molding, the surface thereof usually is not exactly at a right angle for instance to some other portion of the structure with which the hand rail or like structures is to be attached. Subsequent to the erection of concrete or plastic structure and removal of the mold boards, my improved anchoring device remains set in the hardened plastic material. The adjustable member within the hollow base is loose and, by means of threaded studs, bolts or the like, this member may be brought to position with the axis of the threaded aperture thereof at the proper angle to receive a hand rail supported by a similar device on another portion of the structure. The object here is to secure this desirable result by means inexpensive in character and readily adjustable even by unskilled labor in the manner and for the purpose stated. These objects and the several novel features of the invention are hereinafter more fully described and claimed, and the preferred form of construction of an anchoring device embodying my invention is shown in the accompanying drawing in which—

Fig. 1 is an elevation of a stair showing my improved anchoring device as applied thereto and part of a hand rail supported by the anchoring device.

Fig. 2 is an enlarged view partly in section showing the anchoring device in detail.

Fig. 3 is a view showing the manner of attaching the device to a mold board pre-

vious to erection of the structure in which the anchor is to be set.

The device consists of a hollow base preferably formed of the ring like member 1 which is L shaped in cross section as shown in Fig. 2. The inturned flange 2 of the device provides a comparatively large central opening in what is hereafter termed the face of the device, and this flange has the edge formed to provide a spherical seat for the retainer 3 which has the spherical outer surface 4 and a central threaded aperture 5 for the hand rail. This retainer 3 has a flange or lugs 6 provided with threaded apertures for the bolts 7 of which there are four arranged in pairs in diametrically opposite relation. To the flange 8 of the member 1 is secured a sheet metal plate 9 having several apertures 10 therein all within a circle of the diameter of the threaded aperture. To the flange 8 is also secured anchoring members 11 of which there may be several and preferably attached by riveting or welding to the member 1 as shown extending outwardly at an angle to the base. These members provide anchor strips set in the concrete as indicated in Fig. 2. The flange 2 of the member 1 has a series of apertures for the bolts above mentioned which are to be inserted after the structure has been erected.

In Fig. 3 I have shown the device attached to a mold board by nails for instance passing through the apertures 10 of the plate 9. At this time the retainer 3 has the outer face practically flush with the outer surface of the flange 2 permitting the structure to be secured in the manner shown in Fig. 3 to the mold board. These nails may be driven only lightly in the mold board which is usually of wood and thus, after the concrete is set and the anchoring device fixed in position, the mold board may be readily withdrawn and the nails may be cut off or driven into the concrete. The several bolts 7 may then be inserted in the apertures provided therefor in the flange 2 and into the threaded apertures in the flange or lug 6 of the retainer 3 and, by turning the bolts, the retainer is drawn outwardly of the recess of the base to a position similar to that shown in Fig. 2 in which the spherical face of the retainers fits the spherical seat provided in the edge of the flange 2 and, as indicated in the said drawing, the axis of the threaded apertures may be at other than a right angle.

to the surface of the concrete or surface of the flange 2 practically flush therewith. The bolt apertures in the flange 2 are greater in diameter than the bolts 7 permitting the 5 bolt to occupy a position at an angle to the axis of the aperture.

It is to be noted that the bolts 7 are arranged in pairs in diametrically opposite position, as stated, which enables 10 the retainer to be trued relative to the axis of the hand rail member to be secured therein. This is accomplished by threading one or the other of the bolts to a greater extent than the diametrically opposite 15 one of a pair, and the retainer may be trued in two directions for the purpose stated. By this arrangement the device is adapted for use in any position on a horizontal or vertical face of a structure or angular 20 face thereof as may be necessary and can be trued to correct position to receive the hand rail supported at other points on the structure. Thus, if the base, in the hardening of the plastic structure, takes a position 25 not truly flush with the surface thereof or, being flush with the surface, the said surface is not at the proper angle relative to other surfaces of the structure to which the rail is to be attached the retainer, by 30 a simple manipulation of the bolts, may be adjusted to correct position for the purpose stated.

Having thus briefly described my invention, what I claim and desire to secure by 35 Letters Patent of the United States is—

1. An anchoring device for the purpose stated comprising a base adapted to be embedded in concrete, said base being of hollow form and having an apertured face 40 practically flush with the concrete surface, a retainer in the base having a threaded aperture to receive a pipe or the like, and means for fixedly positioning the retainer with the axis of the threaded aperture at 45 any one of a number of angles to the face of the base.

2. An anchoring device for hand rails and the like comprising a base adapted to be embedded in concrete with the face thereof 50 practically flush with the concrete surface, said face having a central aperture the encircling wall of which is spherical in form, a retainer having a spherical portion fitting the said spherical wall and adapted 55 to receive a hand rail, and means for fixedly positioning the retainer in the base in any of a number of positions whereby the hand rail may be set at various angles to the said base, said means being adapted 60 to be adjusted from the exterior of the base.

3. An anchoring device for hand rails and the like comprising a hollow base set 65 in the concrete, anchoring members connected with the base and extending into the body of the concrete, the face of the base

being practically flush with the surface of the concrete and having a central aperture, a retainer in the base having a portion extending through the aperture, the retainer having projecting parts underlying the said 70 face provided with threaded apertures and the face of the base having apertures with which the threaded apertures are adapted to be aligned, and bolts extending through the apertures of the base and in threaded 75 engagement with the threaded apertures of the retainer, the bolt apertures in the base being greater in diameter than the bolts permitting the bolts to stand at other than a right angle to the face and holding the 80 retainer with the axis thereof at a number of possible angles to the face of the base.

4. An anchoring device for hand rails and the like, comprising a base member formed of a ring like portion L shaped in cross 85 section and an attached plate at the bottom, the face of the base being apertured and the wall of the aperture being spherical in form, a retainer for receiving a hand rail consisting of a member provided with a central threaded aperture and spherical outer 90 form to fit the spherical wall of the aperture, the retainer having an extension in the interior of the base having four threaded apertures and the face of the base 95 having apertures with which the threaded apertures are adapted to be aligned, and bolts extending through the apertures of the base in threaded engagement with the retainer apertures, the said bolts being in 100 alignment on diametrically opposite sides permitting the retainer to be set in a number of positions.

5. An anchoring device for hand rails and the like, comprising a hollow metal base 105 having an aperture in the face, the wall of the aperture being spherical in form, a retainer for receiving a hand rail or like structure having a central aperture and a spherical portion to fit the said spherical wall of the aperture, the said retainer being movable relative to the aperture and having at the inner end four threaded apertures, the face of the base also having apertures with which the threaded apertures 110 may be aligned, bolts extending through the said face and in threaded engagement with the said threaded apertures, the bolts being in pairs and in diametrically opposed 115 relation whereby by turning one or other of the bolts the retainer is adjusted with the axis coinciding with the axis of the rail to be inserted in the aperture.

6. An anchoring device for hand rails and the like comprising a base member formed of a ring like portion having an inturned flange at one end and open at the opposite end, a plate attached to the said open end, a retainer in the said ring like portion having a portion of its surface spherical in form 120

and a central threaded aperture, the edge of the said flange being shaped to fit the spherical portion of the retainer, and bolts extending through the said flange to threaded engagement with the retainer so arranged that by the turning of the bolts the retainer is brought to position with the spherical

surface in engagement with the spherical face of the flange and the axis of the threaded aperture set at any predetermined angle ¹⁰ to the said face.

In testimony whereof, I sign this specification.

ROY E. NICHOLSON.
